UNITED STATES PATENT OFFICE

PETER GRAHAM MACGREGOR, OF PEQUANNOCK, NEW JERSEY, ASSIGNOR TO PYRENE MANUFACTURING COMPANY, OF NEWARK, NEW JERSEY, A CORPORATION OF DELAWARE

FIRE EXTINGUISHING APPARATUS

Application filed January 2, 1930. Serial No. 417,917.

This invention relates to fire extinguishing apparatus of the type shown in my parent application Serial No. 230,239, filed November 1, 1927, with respect to which the 5 present application is a continuation in part and from which Patent No. 1,803,859, dated May 5, 1931, has matured.

The subject matter of the present application, in so far as it is taken from the above 10 application, relates to cartridge puncturing mechanism, which is actuated to release the contents of a cartridge containing an expandable fluid, which may serve as a fire extinguishing medium the released fluid being 15 directed to various parts of the motion picture projecting apparatus where a fire is most likely to occur and to where a fire is most likely to spread.

The general object of the present invention 20 may be said to be the providing of a new and improved cartridge-puncturing means, for use in association with a fire extinguishing apparatus of the cartridge type, which will automatically function.

25 Other objects and advantages of the invention will become apparent from the following description, taken in connection with the accompanying drawings in which—

Figure 1 is a fragmental side elevation of 30 a motion picture projecting apparatus having a cartridge puncturing mechanism and a light-obstructing device applied thereto; Figure 2 is a front elevation of the light-obstructing shutter; Figure 3 is a plan view 35 of the shutter; Figure 4 is a fragmental vertical sectional view taken on line 4—4 of Figure 3 with the cover plate of the spring housing omitted and showing in detail a pressure actuated latch releasing device; Figure 40 5 is a vertical sectional view of a cartridge holding and cartridge puncturing mechanism; Figure 6 is a vertical sectional view taken on lines 6—6 of Figure 5 and showing the cartridge puncturing mechanism in elevation; Figure 7 is a horizontal sectional view 45 taken on line 7—7 of Figure 5; Figure 8 is an enlarged view in elevation showing the piercing end of the cartridge puncturing or piercing punch; Figure 9 is a vertical section- 50 al view of the cartridge holding and cart-

ridge puncturing mechanism shown in my above patent; Figure 10 is a view in elevation of the holder and puncturing mechanism, as viewed from the right in Figure 9; Figure 11 is a horizontal sectional view taken 55 on line 11 of Figure 9; Figure 12 is a horizontal sectional view taken on line 12—12 of Figure 9; Figure 13 is a vertical sectional view of a flash pan, taken on line 13—13 of Figure 14; and Figure 14 is a plan view 60 of the flash pan shown in Figure 13.

For the purpose of illustration there is 65 shown in Figure 1, a motion picture apparatus 10 of the type with which the invention herein described is adapted to be used. The motion picture apparatus herein shown includes upper and lower reel compartments 11 and 12, respectively, and an intermediate compartment 13 adapted for the reception of the usual film operating mechanism, there being arranged at the rear of the intermediate compartment 13, the usual lamp compartment 14, adapted for the reception of a suitable source of light, not shown, from which light rays are directed through a hood 15 on to the 70 film as it is intermittantly moved through the intermediate compartment 13.

Upon the motion picture apparatus and adjacent the reel compartment 11 is mounted a 75 cartridge holder and cartridge puncturing mechanism 16, shown in detail in Figures 1 and 5 to 8 inclusive. This cartridge holder and puncturing mechanism includes a barrel 17, within which is confined a compression spring 18, the lower end of which engages the 80 bottom of a removable screw threaded cap 19, carried by the barrel 17, and the upper end of which engages an impact hammer 20 slidably mounted within the barrel 17. Within 85 this impact hammer 20 is slidably mounted a rod 21, the upper end of which is provided with a flange 22 and is adapted to receive the lower end of a cartridge-piercing punch 23, which projects through a stuffing box 24 mounted in the lower end of a housing 25 associated with the upper end of barrel 17. The impact hammer 20 is provided at its 90 lower end with an annular groove, which forms a shoulder 27 adapted to cooperate 95 with a trigger or latch 28, mounted in one of 100

a pair of diametrically opposed slots 29 formed in the barrel 17, the trigger 28 being normally urged inwardly by a flat spring 30, secured to the barrel 17 and maintained in engagement with the trigger 28 at a point adjacent the outwardly projecting notched arm 31 thereof. The trigger 28, when positioned as shown in Figure 5, is adapted to hold the impact hammer 20 in its retracted position 10 against the pressure of the spring 18, and is adapted to release such hammer when a fire occurs, as will hereinafter be explained, so as to allow the hammer 20 to deliver an impact to the flange 22, thus forcing the punch 23 upwardly and through one end of a sealed cartridge 33, which carries a quantity of compressed gas, such as carbon-dioxide, in a liquefied or semi-liquefied condition. The upper end of the housing 25 is formed with a socket 34, having internal screw threads adapted to engage the external screw threads of the neck or reduced end of the cartridge 33, whereby the cartridge may be easily removed, and whereby the reduced end of the cartridge may 20 be firmly maintained in engagement with a packing ring 35, which rests upon the bottom of the socket 34 and surrounds the upper end of the cartridge-piercing punch 23. The housing 25 is counter-bored to provide a chamber 36, which is adapted to communicate with the cartridge 33, when the seal 37 thereof is punctured, and which is connected through an opening 39 with a pipe line 41, having nozzles 42 leading into the compartments 11, 12 and 13.

Within the pipe line 41 is arranged a valve 43, which is normally maintained closed by a flash pan 44, so long as this flash pan is supported in its position shown in Figure 1. 40 When the flash pan is permitted to fall under conditions, which will hereinafter more clearly appear, the valve 43 is permitted to open.

The hammer resetting mechanism includes a yoke, 45, which is pivotally connected to the housing 25, as shown at 46, so that it may be swung to its dotted line position, shown in Figure 6, by an actuating lever 47. In moving the yoke 45 from its position, shown in Figure 5, to its position, shown in Figure 6, a 45 pair of hammer engaging guides 48, having inwardly projecting lugs 49, are moved downwardly through the slots 29 by reason of the connection which is afforded between the lugs 55 49 and the yoke 45 by a pair of connecting links 50, the links being pivotally connected at their upper ends to the yoke 45 and likewise connected at their lower ends to the guides 48. The inwardly projecting lugs 49 60 are adapted to engage the upper end of the impact hammer 20 after such hammer has been released from its retracted position, shown in Figure 5, so that the impact hammer may be forced downwardly against the 65 spring 18 until the latch 28 engages the an-

nular groove 27 of the hammer to hold it in its retracted position.

For temporarily locking the flash pan 44 in its supported position, a fusible link 52 is employed, the link being supported at one end by a pin 53 carried by a suitable fixed part of the apparatus and supported at its other end upon one end of a horizontally disposed arm 54 which is pivotally connected intermediate its ends to a suitable stationary support. 70 The arm 54 is pivotally connected on its outer end to a connecting link 55 which in turn is pivotally connected to a trigger releasing lever 56, pivotally connected near its upper end to the barrel 17 and having its upper end projecting into the notched arm 31 of the trigger 28. Cooperating with the fusible link 52 is a removable pin 58, carried by one side of the flash pan 44 and adapted to be projected into the space afforded intermediate the upper and lower reaches of the fusible link 52. Due to the position of the pin 58 with reference to the fusible link 52, such link serves to retain the flash pan in its position, shown in Figure 1. However, when the link 52 is fused, as by a highly inflammable material carried within the flash pan 44 adjacent a window 44a formed in the compartment 13, the supporting relation of such link with respect to the pin 58 is destroyed and the flash pan 44 is allowed to drop, thus permitting the valve 43 to open and allowing the horizontally disposed link 55 to move to the left, as viewed in Figure 5, under the influence of a tension spring 59, having one end 80 connected to such link and its other end anchored to a stationary part of the apparatus. As the link 55 is thus moved, the lever 56 is so actuated as to move the trigger 28 outwardly, thereby releasing the impact hammer 20, whereupon the spring 18 forces such hammer against the flange 22 of the rod 21 with sufficient force to project the pointed end of the piercing punch 23 through the seal 37 of the cartridge 33. As the cartridge is pierced, 85 its contents escapes into the chamber 36, as a gas under pressure, from which chamber it passes into the compartments 11, 12 and 13 through the pipe line 41 and its associated nozzles 42.

If desired the cartridge holding and puncturing mechanism shown in Figures 1 and 5 to 8 inclusive may include a suitable holder 60, into which the screw threaded neck portion of a reserve cartridge 33* may be 110 screwed. The reserve cartridge 33* may be readily removed from its holder 60 and inserted into the socket 34 when it is desired to recondition the apparatus for use after a conflagration has resulted in the puncturing of 115 the cartridge 33.

In order that the opening, when formed in the diaphragm 47 by the punch 23, may not be obstructed by the piercing end of the punch, such piercing end, although pointed, is 120 125 130.

- formed with an enlarged head portion 61, which is of a greater diameter than the shank portion 23a of the punch. It will be appreciated that the head portion 61 makes a relatively large opening in the diaphragm 37 and that this opening is of such a size with respect to the shank portion 23a of the punch that a substantial clearance is afforded between such shank portion and the edge of the opening made by the head 61 as it passes through the diaphragm, the clearance thus afforded being sufficient to insure unhampered escape of the contents of the container when a fire occurs.
- 15 In case of fire, the motor 63 employed for operating the film mechanism of the picture projecting apparatus should be instantly stopped, and to accomplish this, an auxiliary switch 64 is disposed in the motor circuit in addition to the main switch, not shown. This auxiliary switch 64 may be of the usual double-push-button type cooperating with suitable pressure actuated means, such as is shown in my above application, for automatically opening the motor circuit upon the happening of a fire, the pressure fluid being supplied to such pressure actuated means through a pipe line 65 connected to the pipe line 41. By the use of such pressure actuated means, it will be appreciated that as soon as the contents of the cartridge 33 is released, the switch 64 may be instantly actuated to open the motor circuit, thereby stopping the operation of the picture projecting apparatus.
- When the film actuating mechanism of the picture projecting apparatus is stopped by reason of opening the circuit of the motor 63 upon the occurrence of a fire, it is desirable to interpose an obstruction between the source of light and the stationary film; and to this end an automatically actuated light obstructing device 67 is provided. This light obstructing device includes a shutter 68, connected to an arm 69, carried by a shaft 70, journalled in the wall of a housing 71 and projecting into such housing. Within the housing 71 is mounted a coil spring 72, one end of which is connected to the shaft 70 and the other end of which is anchored to the inner wall of the housing, the spring being adapted to insure movement of the shutter 68 from its position shown in Figure 4 to its position shown in Figures 1, 2 and 3 when it is released, either automatically or manually, as will hereinafter appear. The outer end of the arm 69 serves as a handle by which the shutter 68 may be moved from its position shown in Figures 1 to 3 inclusive to its position shown in Figure 4, and carries a latch pin 73, which is adapted to engage a stop 74 carried by the housing 71, the stop being adapted to limit the closing movement of the shutter so as to insure its assuming a proper position with respect to the hood 15 for completely obstructing the light rays. Also, the latch pin 73 cooperates with a latch lever 75, whereby the shutter 68 is held in its position shown in Figure 4 during the operation of the motion picture projecting apparatus. This latch lever 75 is pivotally connected to a suitable support 76 and is provided with a handle 77, by which the lever may be manually moved to release the shutter, the lever being held in shutter-latching position by a compression spring 78 interposed between one end of such lever and a suitable stop or lug 79 associated with the housing 71.
- 10 15 20 25 30 35 40 45 50 55 60 65 70 75 80 85 90 95 100 105 110 115 120 125 130
- In order that the latch lever 75 may be automatically released when the operation of the motion picture apparatus is automatically discontinued, as above described, there is provided a pressure actuated device 80. This pressure actuated device includes a cylinder 81, having a reciprocating piston or plunger 82 arranged therein, one end of which is adapted to engage a lug or button 83 carried by the lever 75 and projecting into the housing 71. The cylinder 81 is connected at one end of the piston 82 to a pressure pipe 85, which, in turn, is connected to the pipe line 41, so that when the cartridge 33 is punctured, pressure is delivered to the cylinder 81, thereby causing the piston 82 to move outwardly into engagement with the lug 83 and release the latch 75, whereupon the shutter 68 is quickly moved by the spring 72 from its position shown in Figure 4 to its position shown in Figures 1 to 3.
- The form of cartridge holding and puncturing device shown in Figures 9 to 12 inclusive is substantially identical with the cartridge holding and puncturing device shown in Figures 1 and 5 to 8 and above described, and in so far as the common structure is concerned corresponding numerals, primed, are employed to indicate corresponding parts.
- This latter form of device, however, is designed particularly for use with a smaller cartridge 33', the reduced end of which is not screw threaded. Due to the difference of the cartridge 33' over the cartridge 33, the housing 25' is provided with a cartridge cup 90, which is screwed into the socket 34' and is so shaped as to conform to the neck portion of the cartridge 33'. This cartridge cup 90 also serves to hold a cartridge-neck-engaging washer 91 in place upon the flange end 92 of a stuffing box 93, carried by the housing 25', through which stuffing box the cartridge piercing punch 23' of the device is adapted to operate. In this form of the invention, the cartridge 33' is held in its seated position by a pressure screw 94 having screw threaded engagement with the cross member of the yoke 45', the head of the pressure screw being adapted to engage the upper end of the cartridge, as shown.

It will be understood that the impact hammer 20', in this form of the invention, is set or retracted by moving the yoke 45' from its position, shown in Figure 9, to its position shown in Figure 10, and that the impact hammer is released through the operation of the release lever 56' upon the occurrence of a fire, with the result that the cartridge 33' is punctured and its contents are rendered available for use either as a fire extinguishing medium or as a medium by which a fire extinguishing liquid may be expelled from a suitable receptacle, not shown, to which the pipe line 41 may lead, as disclosed in my above patent. Also, it will be understood that the auxiliary switch 64 and the shutter actuating means, both of which are shown in Figure 1, may be operated by the pressure rendered available from the cartridge 33', when this form of the invention is employed; and that the automatic actuation of this form of cartridge holding and puncturing mechanism may be effected through the same instrumentalities, namely, the flash pan 44 and its associated parts, hereinbefore described in connection with the form of cartridge holding and puncturing mechanism shown in Figures 1 and 5 to 8 inclusive.

It will be understood that various changes may be made with respect to the invention herein shown and described without departing from the spirit of the invention or the scope of the following claims:

What is claimed is:

1. Means for puncturing a cartridge containing an expansible fluid, comprising a housing adapted to receive the end of the cartridge to be punctured, means for holding the cartridge seated within said housing, a reciprocatory rod having a piercing punch adapted to be driven through the end of the cartridge to be punctured, an impact hammer actuating spring surrounding said rod, an impact hammer slidable upon said rod and adapted to be set in a retracted position against the influence of said spring and to engage a portion of said rod to drive the piercing punch through the end of the cartridge to be punctured, a trigger for holding said hammer in its retracted position, and trigger actuating means for releasing said trigger whereby said hammer is permitted to deliver a cartridge piercing blow to drive the piercing punch through the end of the cartridge to be punctured.

2. Means for puncturing a cartridge containing an expansible fluid, comprising a housing, a cartridge cup, means for holding the end of the cartridge to be punctured seated within said cup, a reciprocatory rod having a piercing punch slidably within said housing and provided with a hammer-engaging portion, an impact hammer-actuating spring surrounding said rod, an impact hammer slidable upon said rod and adapted to

be set in a retracted position against the influence of said spring, a trigger for holding said hammer in its retracted position, and trigger actuating means for releasing said trigger whereby said hammer is permitted to deliver a cartridge piercing blow to the hammer engaging portion of said stem to force the piercing punch through the end of the cartridge to be punctured.

3. Means for puncturing a cartridge containing an expansible fluid, comprising a housing adapted to receive the end of the cartridge to be punctured, means for holding the cartridge seated within said housing, a barrel associated with said housing, a reciprocatory rod within said barrel and having a piercing punch adapted to be driven through the end of the cartridge to be punctured, an impact hammer-actuating spring surrounding said rod, an impact hammer slidable upon said rod and adapted to be set in a retracted position against the influence of said spring and to engage a portion of said rod to drive the piercing punch through the end of the cartridge to be punctured, a trigger projecting into said barrel for engaging said hammer and holding the same in its retracted position, and trigger-actuating means for releasing said trigger whereby said hammer is permitted to deliver a cartridge piercing blow to drive the piercing punch through the end of the cartridge to be punctured.

4. Means for puncturing a cartridge containing an expansible fluid, comprising a housing having a chamber formed therein adapted to receive the end of the cartridge to be punctured, a cartridge cup, pressure means for holding said cartridge seated within said cup, a rod having a flange thereon and terminating in a piercing punch, said piercing punch projecting into said chamber, an impact hammer-actuating spring surrounding said rod, an impact hammer slidable upon said rod and adapted to be set in a retracted position against the influence of said spring, a trigger for holding said hammer in its retracted position, and trigger actuating means for releasing said trigger, whereby said hammer is permitted to deliver a cartridge-piercing blow to said flange to be transmitted to said punch.

5. Means for holding and puncturing a cartridge containing an expansible fluid, comprising a barrel, a cartridge cup adapted for the reception of a cartridge to be punctured, a pivoted yoke connected to said barrel, releasable pressure means carried by said yoke for holding said cartridge in said cup, said yoke being adapted to be swung about its pivotal connection with said barrel when said pressure means is released from said cartridge, a piercing punch, a spring pressed impact hammer adapted to be set in a retracted position, impact hammer resetting means connected to said yoke and adapted to

be moved when said yoke is swung about its pivotal connection with said barrel for moving said impact hammer to its retracted position, a trigger for holding said hammer in its 5 retracted position against the influence of said spring, and trigger actuating means for releasing said trigger whereby said hammer is permitted to deliver a cartridge piercing blow to said punch.

10 In testimony whereof, I have affixed my signature to this specification.

PETER GRAHAM MacGREGOR.
